CLAIM

The ornamental design for a handle of an oral care implement, as shown and described.

DESCRIPTION

FIG. 1 is a front perspective view of an handle of an oral care implement according to the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings formed by linear segments of equal length illustrate portions of the article that form no part of the claimed design. The broken lines in the drawings formed by a dash-dot-dash sequence illustrate an unclaimed boundary.

1 Claim, 4 Drawing Sheets
